UNITED STATES PATENT OFFICE.

PAUL F. ELLMER AND CHARLES STREFF, OF PHILADELPHIA, PENNSYLVANIA.

ELEVATOR CONSTRUCTION.

1,241,724.

Specification of Letters Patent.

Patented Oct. 2, 1917.

Application filed February 21, 1917. Serial No. 150,002.

To all whom it may concern:

Be it known that we, PAUL F. ELLMER and CHARLES STREFF, citizens of the United States, residing at Philadelphia, in the 5 county of Philadelphia and State of Pennsylvania, have invented certain new and useful Improvements in Elevator Constructions, of which the following is a specification.

10 Our invention consists of improvements in elevator constructions, one of its objects being to provide means whereby the elevator car cannot be moved while the gate or door at a floor level is open.

15 Another object is to provide means whereby the opening movement of said gate or door will automatically operate to stop the movement of the car adjacent the level of the floor at which the gate is located.

20 Another object is to provide means whereby locking means for the door or gate can be actuated either from the elevator car or from a floor level.

25 A still further object is to provide mechanism whereby said latter means can be operated only when the car has reached the floor level.

30 Another object is to so make the elements of our invention that they will be durable and of comparatively simple construction.

35 These objects, and other advantageous ends which will be described hereinafter, we attain in the following manner, reference being had to the accompanying drawings in which—

Figure 1 is a front elevation of an elevator construction made in accordance with our invention.

40 Fig. 2 is a fragmentary side elevation of Fig. 1.

Fig. 3 is a front elevation showing certain of the elements of our invention which are located adjacent the floor level of a building and drawn on a larger scale than illustrated 45 in Fig. 1.

Fig. 4 is a fragmentary section through the floor of an elevator car provided with means forming a part of our invention.

50 Fig. 5 is an enlarged fragmentary elevation showing a pivoted cam shoe and means whereby the cam shoe is moved on its pivot, the same forming a part of our invention.

Fig. 6 is a section on the line 6—6 of Fig. 5.

55 Referring to the drawings, 1 and 2 represent the side walls of a building including

an elevator shaft or well 3. One floor of the building is illustrated at 4, and a gate 5 is designed to close the space between the floor level and the elevator well. This gate as 60 illustrated is of the type used on freight elevators and is designed to be raised and lowered into position. The means for raising the gate consists of a rope 6 which is attached to the upper rail 7 and this rope 65 passes over anti-friction rollers 8 and 9 mounted on a super-structure 10.

A weight 11 is suspended from the opposite end of the rope 6 and is heavier than the gate 5, so that said weight acts to automatically raise said gate if the latter is released 70 in a manner hereinafter described.

The gate 5, at its bottom, has a depending bar 12 secured thereto, said bar having a notch 13 adjacent its lower end. This bar, 75 when the gate is in its lower or closed position, moves between the side walls of a casing 14, said casing being secured to the floor 4 and forming a pivotal support and housing for a double ended locking lever 15. 80 The locking lever 15 has a hooked upper end 16 designed to enter the notch 13 in the bar 12 and thereby retain said gate in a lower position against the action of the weight 11.

The locking lever 15 has extensions 17 and 85 18 thereon. The extension 17 is connected by a coiled spring 19 with a detent 20, the latter being in the form of a projection on a lever 21 which is pivoted at 22 within the casing 14.

90 The lever 21 has an end 23 which projects out of said casing 14, and has thereon an anti-friction roller 24. The end 23 of the lever 21 is limited in its upward movement by the side wall 25 of the casing 14, hence 95 the spring 19 serves to normally keep the hooked end 16 of the locking lever 15 within the notch 13 of the bar 12 and to keep the detent 20 in line with the extension 18 on said locking lever 15, so that with the levers 100 in said position, the gate 5 will be positively locked.

The lower end of the locking lever 15 has a link 26 pivotally connected thereto, said link having an anti-friction roller 27 pivoted 105 thereon within its length, the opposite end of said link being in pivotal connection with a hand operated lever 28 which is mounted on the floor 4.

110 The lever 28 cannot be operated while said levers 15 and 21 are in the positions above described as is obvious from the fact that

the lever 15 cannot be moved while the detent 20 is in line with the extension 18. However, means is provided on the elevator car 29 by which the detent 20 is moved out 5 of alinement with the extension 18 to permit rocking movement of said lever 15 to release the bar 12. This means consists of a cam 30 secured to the bottom of the elevator car 29, so that when said car approaches, in either 10 direction, the anti-friction roller 24, it will engage the latter and swing the lever 21 into such position as to free the extension 18 of the locking lever 15 of the detent 20.

It will be noted, however, that when said 15 action takes place, the car 29 will be substantially at the floor level. Furthermore, it will be noted the cam 30 does not move the locking lever out of locking engagement, but merely permits the locking lever to be 20 rocked either by the movement of the hand operated lever 28 or the movement of a hand operated lever 31 on the car 29. This lever 31, at its lower end, is pivotally connected to a rod 32, the latter being slidable through a head 33 which is freely rotatable in a cam shoe 34, the latter being pivoted at 35 to the side 36 of the car 29.

The rod 32 at its free end is threaded and provided with a nut 37, and a coiled spring 30 38 is interposed between the head 33 and the nut 37. If it is desired to release the gate 5 by a person on the car 29, the lever 31 is operated to move the cam shoe 34 into such position that said cam shoe will move the 35 anti-friction roller 27 on the link 26 in the direction of the length of said link.

The arrangement and location of the cam shoe 34 and the cam 30 should be such that the cam 30 will have moved the lever 21 40 prior to the engagement of the cam shoe 34 with the anti-friction roller 27, so that when said cam shoe engages said roller 27, the detent 20 will have been moved out of alinement with the extension 18, thus permitting 45 the rocking movement of said lever 15. Hence, the gate 5 can be released by the movement of either of the hand operated levers 28 or 31 when the car 29 approaches the floor level.

50 The raising of the gate 5 operates to automatically stop the car through the operation of the following mechanism:—

A depending bracket 39 is secured to the super-structure 10 and has pivoted thereon 55 a lever 40, the latter having a long end 41 and a relatively short end 42. This lever 40 is designed to be swung on its pivot by the engagement therewith of a roller 43, the latter being carried by the upper rail 7 of the gate 5.

The short end 42 of the lever 40 has a hole 42^a therein through which passes a cable 44, the latter running throughout the length of the elevator well. The upper end of the

cable 44 is attached to a chain 45 which 65 passes around a grooved pulley or sheave 46.

The chain 45 has one of its links secured to the pulley 46 by means of a screw 47 or other suitable means. This pulley 46 is keyed to and rotatable with a shaft 48 having the usual pulley 49 thereon over which 70 passes the cable 50 for manually starting and stopping the movement of the elevator.

The attachment of said cable 44 with the chain 45 is such that when the cable 34 is 75 pulled downwardly, the pulley 46 will be rotated to such extent that it will stop the movement of the car 29, it being noted that the shaft 48 is attached to means (not shown) for controlling the power by which 80 the elevator is operated. In other words, the rotation of the pulley 46 by the cable 44 is such that it will rotate the shaft 48 to the same extent as it is necessary to rotate said shaft by the movement of the cable 50 when 85 it is desired to stop the elevator by the manual movement of said cable 50.

In order to move the cable 44 as above noted, we preferably provide a clamp 51 on said cable, said clamp being of greater 90 width than the diameter of the hole 42^a in the lever 40, so that when said lever 40 rocks on its pivot, the short end 42 thereof will engage the clamp 51 and thereby pull the cable 44 to effect the stopping of the elevator 95 car.

The cam shoe 34 and the cam 30 can be made of such lengths that they will release the locking means for the gate prior to the arrival of the car at the floor level, however, it will be noted that it takes but a short 100 time for the gate 5 to rise to effect the stopping of the elevator, so that the time elapsing between the release of the locking means and the arrival of the car at the floor 105 level will be sufficient to permit the upward movement of the gate and the actuation of the means whereby the car is stopped.

It will be noted that when the gate is raised, it will be impossible to start the car 110 in view of the fact that the cable 44 will hold the pulley 46, and consequently the shaft 48 against rotation. Therefore, in order to start the car it is necessary to manually lower the gate 5 to release the 115 clamp 51 from engagement with the end 42 of the lever 40. The cable 50 can then be operated in the customary manner to effect the rotation of the shaft 48 and thereby start the movement of the car 29.

While we have described but one floor and one gate and the elements operative to lock said gate, it will be noted that our improved elevator can be installed in buildings having any number of floors, since the 125 mechanism will operate similarly in connection with the gate at any floor level.

While we have described our invention as

taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

10 Having thus described our invention, what we claim as new and desire to secure by Letters Patent is:

1. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, a casing inclosing said levers and including a wall having an opening therein through which a portion of said detent lever extends, said wall forming means for limiting the movement of said detent lever in one direction, and a spring connecting said locking lever and the detent lever whereby the detent lever is held in engagement with said wall and the locking lever is moved toward said means on the gate, substantially as described.

2. The combination in an elevator construction, of a movable gate, a car, means for normally locking the gate in its closed position and including a detent for preventing movement of said locking means, means operative to move said locking means when the detent has been moved out of operative position, means operated through the medium of movement of said car for moving the detent into an inoperative position, means operative by the opening movement of said gate to stop said car, and means for automatically moving said gate to its open position, substantially as described.

3. The combination in an elevator construction, of a movable gate, a car, means for normally locking the gate in its closed position and including a detent for preventing movement of said locking means, means operative to move said locking means when the detent has been moved out of operative position, means carried by the car for moving said detent, means carried by the car for moving the locking means into an inoperative position, and means for automatically opening said gate when the locking means is moved into said inoperative position, substantially as described.

4. The combination in an elevator construction, of a movable gate, a car, means for normally locking the gate in its closed position and including a detent for prevent-

ing movement of said locking means, means operative to move said locking means when the detent has been moved out of operative position, means carried by the car for moving said detent, means carried by the car for moving the locking means into an inoperative position, means for automatically opening said gate when the locking means is moved into said inoperative position, and means operated by said gate during its opening movement to effect the stopping of the car, substantially as described.

5. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, and means on said car for moving said locking lever into an inoperative position to release said gate, substantially as described.

6. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, means on said car for moving said locking lever into an inoperative position to release said gate, means for moving said gate to an open position, and means operative by the opening movement of said gate to effect the stopping of the car, substantially as described.

7. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, and means adjacent said floor for moving said locking lever into its inoperative position, substantially as described.

8. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever,

means adjacent said floor for moving said locking lever into its inoperative position, and means on said car for moving said locking lever into its inoperative position, substantially as described.

9. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, means adjacent said floor for moving said locking lever into its inoperative position, means for automatically moving said gate into its open position, and means operated by the opening movement of said gate to effect the stopping of the car, substantially as described.

10. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, means adjacent said floor for moving said locking lever into its inoperative position, means on said car for moving said locking lever into its inoperative position, means for automatically moving said gate into its open position, and means operated by the opening movement of said gate to effect the stopping of the car, substantially as described.

11. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, means for limiting the movement of said detent lever in one direction, a spring connecting said locking lever and the detent lever whereby the detent lever is held in engagement with said limiting means and the locking lever is moved toward said means on the gate, and means for moving said locking lever to free said means on the gate, substantially as described.

12. The combination in an elevator construction, of a supporting structure including a floor, a movable gate, a car, a locking lever, a detent lever, means on said gate for

engagement with the locking lever, a detent on said detent lever designed to normally prevent movement of said locking lever, means on said car for actuating said detent lever to move the detent out of the path of movement of said locking lever, a link connected to said locking lever, and a hand operated lever connected to said link whereby the locking lever can be manually moved into an inoperative position, substantially as described. 75

13. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, a link connected to said locking lever, a hand operated lever connected to said link whereby the locking lever can be manually moved into an inoperative position, a cam shoe on said car operative to automatically move said locking lever into an inoperative position after the detent has been moved out of alignment therewith, substantially as described. 85

14. The combination in an elevator construction, of a supporting structure including a floor, a movable gate, a car, a locking lever, a detent lever, means on said gate for engagement with the locking lever, a detent on said detent lever designed to normally prevent movement of said locking lever, means on said car for actuating said detent lever to move the detent out of the path of movement of said locking lever, a link connected to said locking lever, a hand operated lever connected to said link whereby the locking lever can be manually moved into an inoperative position, an anti-friction roller carried by said link, a cam shoe movably mounted on said car and normally out of the path of said anti-friction roller, and means for moving said shoe into the path of said anti-friction roller whereby the locking lever is automatically moved into an inoperative position to free the gate, means for automatically opening the gate when thus freed, and means operated by the opening movement of said gate to effect the stopping of the car, substantially as described. 95 100 110 115

15. The combination in an elevator construction, of a gate, means for normally locking the gate in a closed position, a car, means operative to effect movement of the car, means for moving said locking means into an inoperative position to free the gate, means for automatically raising the gate when thus freed, a cable movable to effect 125 120

the stopping of said car, and a lever movable by the opening movement of said gate and operative to move said cable to effect the stopping movement of the car, substantially as described.

16. The combination in an elevator construction, of a gate, means for normally locking the gate in a closed position, a car, means operative to effect movement of the car, means for moving said locking means into an inoperative position to free the gate, means for automatically raising the gate when thus freed, a cable movable to effect the stopping of said car, and a lever having a hole therein through which said cable passes, means movable in conjunction with said cable and of larger cross section than the cross section of said hole in the lever, said lever being movable by said gate to actuate said means on the cable, whereby the latter is moved to effect the stopping of the car, substantially as described.

17. The combination in an elevator construction, of a gate, means for normally

locking the gate in a closed position, a car, 25 means operative to effect movement of the car, means for moving said locking means into an inoperative position to free the gate, means for automatically raising the gate when thus freed, a cable, a pulley operatively connected to said second means, a flexible member surrounding said pulley and secured thereto, said cable being attached to said flexible member, a lever movable by the opening movement of said gate 30 and operative to move said cable to actuate said pulley through the medium of said flexible device and thereby effect the stopping of the car, substantially as described.

In testimony whereof we have signed our names to this specification in the presence of two subscribing witnesses.
